[57] CLAIM

The ornamental design for a bolt, as shown and described.

DESCRIPTION

FIG. 1 is a top and front perspective view of a bolt, showing my new design;

FIG. 2 is a bottom perspective view of the same in its inverted state;

FIG. 3 is a front elevational view thereof;

FIG. 4 is a top plan view thereof;

FIG. 5 is a bottom plan view thereof;

FIG. 6 is an elevational view thereof, taken at 45 degrees from FIG. 3; and,

FIG. 7 is a longitudinal cross sectional view thereof taken along lines 7—7 of FIG. 4.
